UNITED STATES PATENT OFFICE.

CHARLES W. MUELLER, OF ST. LOUIS, MISSOURI, ASSIGNOR, BY MESNE ASSIGNMENTS,
TO ARBETTER FELLING MACHINE COMPANY, A CORPORATION OF MAINE.

BLINDSTITCH SEWING MACHINE.

Application filed June 28, 1918. Serial No. 242,355.

To all whom it may concern:

Be it known that I, CHARLES W. MUELLER, a citizen of the United States, residing in the city of St. Louis and State of Missouri, have invented new and useful Improvements in Blindstitch Sewing Machines, of which the following is a specification.

My invention relates to improvements in blind-stitch sewing machines, and has for its general object to provide an improved machine of the vibrating-needle type, in which the needle may be caused to move laterally, to change its path of reciprocation, between successive thrusts, for the formation of two rows of stitches. More specifically my invention provides an improved machine for felling the edge of an overlying layer of fabric to the body or base layer, and it consists in the novel features of construction and arrangement hereinafter described and claimed. The combinations and arrangements of parts wherein my invention is embodied may best be understood by reference to the accompanying drawings wherein—

Fig. 1 is a side elevation, with parts in section, of a complete machine forming one embodiment of my invention;

Fig. 2 is a front view of the "stitching head" and associated parts, principally in elevation, with parts in section;

Fig. 3 is a vertical section on line 3—3 of Fig. 2;

Fig. 4 is a fragmentary section on line 4—4 of Fig. 3;

Fig. 5 is a horizontal section on line 5—5 of Fig. 2;

Fig. 6 is a sectional view on line 6—6 of Fig. 5;

Figs. 7, 8 and 9 are perspective views showing fragments of the stitch-forming mechanism in successive progression of operating positions;

Figs. 10, 11, 12 and 13 are sectional elevations showing portions of the feed mechanism in successive operating positions;

Fig. 14 is a detail section on line 14—14 of Fig. 10;

Fig. 15 is a detail of the slide-nut construction of the feed;

Fig. 16 is an elevation, with parts broken away, of the underside of the machine;

Fig. 17 is a plan detail of the clamp plate;

Fig. 18 is a section therethrough;

Fig. 19 is a diagram illustrating the seam made by the machine;

Fig. 20 is a detail of the plunger and stop-lever;

Fig. 21 is a section on line 21—21 of Fig. 1.

I have illustrated my present invention as embodied in a machine comprising a frame 25 having a lower arm 26 that carries the work-handling mechanism; a post 27 that houses the vertical shafting; and the upper arm 28 that supports the main shaft and has at its end the arcuate bearing arm 29 in which is mounted the stitching head 30. The stitching head is so constructed that the stitching center, or point of cooperation of the needle with the work is, at approximately the center of the arc of arm 29 and the head carries at its lower extremity a presser foot 31 for cooperation with the stitch-forming, feeding, and work-handling mechanisms. The upper portion of the head-carried mechanism is housed in a cover 32.

The specific work for which my machine is designed, in the particular embodiment shown, is substantially that accomplished by the machine shown in U. S. patent to John G. Lewis, No. 862,830.

In the present machine the head-shaft 35 (Fig. 3), driven by a gear-couple 36 from the main shaft 37, carries the counterbalanced crank arm 38, the wrist pin 39 of which operates a link 40, the lower arm of which (Fig. 4) engages the wrist pin 41 of the needle arm 42 which is slidably pivoted between its ends, has its wrist pin slidably through the link 40, and at its forward end carries the needle 43. This train of mechanism imparts lengthwise reciprocation to the curved needle to make one reciprocation during each revolution of the head-shaft, and leaves the needle-arm free to be vibrated laterally.

The needle bar is vibratable along its pivotal axis through a range that is variable by

adjustment. As shown in Fig. 4 the needle bar 42 is fast on a sleeve 45 that may slide along the hollow pivot-stud 46 fixed to the stitching head 30, its movement in one direction being subject to adjustable limitation by head 47 of an adjusting spindle 48 that extends through the center of the pivot 46. This spindle makes threaded engagement with a knurled nut 49 for retraction 10 of the head 47 against the tension of a spring 50, which is interposed between the bottom of a recess in the pivot 46 and the enlarged part of the spindle 48, and the spindle is prevented from turning with the nut as by a feather 51. The sleeve 45 is engaged by a shifter lever 53 which is pivoted at its upper end as at 54 and is acted on by spring 55 that tends to throw the needle bar toward the adjustable spindle-head 47 and so serves to maintain a roller 56 on the shifter lever in contact with a cam 57 which constitutes the positively moved part for vibrating the needle. The shaft 58 for this cam 57 extends through the rear wall of the head frame 30 and is driven from the head-shaft 35 through an upright connecting shaft 59 by means of appropriate spiral gear couples 60 and 61 (Fig. 3) which rotate the cam shaft in one-to-two relation to the head shaft. The cam 57 is cut to present diametrically opposed arcs of different radius joined by smooth intermediate curves, and the radius-difference of these arcs measures the maximum vibration of the needle. The arc of larger diameter throws the needle to its non-variable or leftward limit of throw and the arc of lesser diameter permits the needle bar to move laterally under the influence of spring 55 to such extent as is determined by the adjustment of the spindle 48.

The stitch-forming mechanism of course includes suitable thread-guiding, controlling, and take-up devices, and some form of loop-taker which (in a lock-stitch machine as herein shown) may be a suitable rotary hook 62 carrying a second thread bobbin in conventional manner. This rotary hook 62 is driven from the vertical head-shaft 59, and is located close to the back wall of head 30, above the presser foot, but these parts require no specific description.

In the form shown the needle strikes from the front of the machine rearwardly at some suitable angle to the line of feed, such angle being determined to suit particular conditions of work to be performed, and in this instance being shown as about twenty degrees.

The needle in its reciprocation travels over the upper surface of the presser foot 31, that is rigidly secured to the lower portion of the stitching head and that is provided with an opening 66 through which the work, fed along the underside of the

presser foot may be presented to the operation of the needle.

The present construction of machine is particularly well adapted for the felling of a raw or folded edge of an overlying layer 70 of material to a base layer by means of two connected rows of stitches, one of which engages only the underlying or base layer and the other of which engages only the overlying layer or layers of material. For this 75 purpose the overlying layer of material may well be presented to the needle through the opening 66 with the on-feeding portion (i. e. the portion approaching the stitching point under the influence of the feed) of 80 the overlying material traveling above the surface of the presser foot and the on-feeding portions of the base material traveling beneath the presser foot, so that the needle, on its reciprocation in one (the rightward 85 one) of its two paths may enter under the edge of the overlying layer of material to strike diagonally upwardly through such layer alone, while on its other reciprocation (along the leftward line) the needle 90 may enter and emerge from the upper surface of the base layer only, the latter being elevated through the opening 66 to receive the needle-thrust, as by means of a plunger 68. The off-feeding (already stitched) portions of the work pass below the presser foot, both as to the base and overlying layers, and of course appropriate work-holding means is provided in conjunction with suitable feed mechanism, to effect proper handling of 95 the fabric.

The presser foot shown, see Figs. 7 and 14, is cut away as at 70 on the rightward side, to leave open, as at 71, a chord of the work-opening 66 of the presser foot, the angle between the openings constituting a lifting point 72, the edge of which is preferably slightly upturned as at 73. In front of, or toward the operator with respect to, the lifting point 72 an edge-guide in the form of elevation 74 is provided, this guide being arranged to direct the edge of the overlying layer of fabric, as it is being fed, along a line that intersects the leftward path of reciprocation of the needle well back of the stitch-forming position, so that the needle will not engage the guided edge when making this leftward thrust, but may engage the edge when the needle has been vibrated to its alternative, rightward path of reciprocation.

The presser foot is thinned as at 75 along the area over which the needle moves, and is also slotted on parallel lines as at 76 to receive the feed dog, to be described, and it is preferably provided with a leaf-spring extension 77 that serves as a needle guard to prevent injury to the operator's fingers, and as a guide to facilitate rapid insertion of the work. This guard, attached to the bridge- 125

the present machine I have provided a plunger-adjustment novel in structure and functioning. In association with the plunger proper I provide an adjustable element that 5 will coact with the presser foot (indirectly, by acting directly against the underside of the clamp member 83 which in turn works against the goods underlying the presser foot) close to the work-opening and will 10 function to check the rise of the plunger positively at different elevations according to the thickness of the goods-layer or layers encountered by the adjustable element. This element which I designate the "plunger-stop" I preferably construct as an angular lever 135, pivoted as at 136 to the plunger, having its upper end slightly below and in line with the plunger end or tip, and arranged to coact 15 with the underside of the clamp-member 83, and having its rear end connected with the means for effecting the stop-adjustment or variation of relative position as between the tip of the stop and the tip of the plunger-proper. Thus the stop lever may be a stamping with a circular pivot head 137 struck thereon to engage a receptive recess 138 in the plunger-lever 120, the stop lever taking shape corresponding with the plunger lever at its front end, and near its rear end 20 being deflected to run alongside of the plunger lever. Its rear end is slotted as at 139 and engages a crank portion 140 of the shaft 121 which is mounted rotatably and provided, at the front of the machine with 25 a knurled head 141. Manifestly when the stop lever encounters sufficient resistance to upward movement it holds the plunger against further rise and spring 124 yields to permit bell-crank 123 to complete its 30 throw. It will be apparent that adjustment may be made while the machine is running.

In the operations of the machine the work, consisting, say, of a base layer A of fabric which may be of relative heavy material, an overlying layer of fabric B, presenting a raw or folded edge b to be felled to the base layer, is inserted in the machine with the edge of the overlying layer along the line defined by the edge guide 74 of the 35 presser foot, the portion of this edge that is ready to be stitched lying over the guiding point 73 and being thereby raised somewhat above the level of the base layer. In this condition the work is fed to the machine by the overhead feed that, in virtue of its positive engagement with the upper surfaces of both layers, advances them equally, substantially eliminating slip between the 40 layers. When, now, the stitching is in progress, with the transverse range of needle vibration appropriately adjusted, the needle, effecting its stroke on the leftward path of reciprocation, will enter and emerge from the upper or stitching surface of the base 45 layer A of material, the latter being bent

in a node through the presser foot opening by means of the plunger 68 which rises before the needle reaches its point of penetration and recedes when the needle has properly passed into and out of the goods. 50 The usual cooperation of the thread-carrying needle with the second-thread-carrying hook mechanism results in the formation of a lock stitch slightly diagonal to the direction of feed and local to the base layer of the 55 fabric. Then after the needle has retracted and a feed movement has taken place the needle makes its second stroke along its rightward path of reciprocation so that its point enters under the raised edge of the 60 overlying layer B and emerges from the upper side thereof back from the edge, and, in cooperation with the loop-taking mechanism, lays a second stitch on a line parallel with the first, but local to the overlying layer 65 of material. This process continues, the tension exerted on the threads drawing the superimposed layer down upon the base layer and rolling its edge, if folded, so that the needle thread, the runs of which lie 70 wholly on the surface of the base fabric and substantially or completely concealed, and only the runs of bobbin thread n' which 75 pass over the edge of the overlying layer B are exposed to view.

While I have herein described my invention in one working embodiment only, it will be apparent that its novel features may be varied in details of structure and arrangement without departure from my invention 100 within the scope of the appended claims.

I claim:

1. In a sewing machine for blind-stitching, the combination with an apertured presser-foot, stitch-forming means working above said presser-foot, plunger means working below and through said presser-foot, work-feeding means, and work-clamping means below said presser foot comprising a work-plate having a work-contacting 105 surface and a clamp-bar carried by said work plate, yieldable relative thereto, and having a work-contacting surface.

2. In a sewing machine for blind-stitching, the combination with a presser-foot, stitch-forming mechanism above said presser-foot and including a needle, feeding means arranged above and working through said presser-foot and having laterally separated feed-points between which the needle 110 works, and a work-holding clamp below said presser-foot cooperating with the underside thereof and having respective surfaces presented to both feed-points, the portion of said clamp presenting a surface to one feed 115 point being yieldable with reference to the portion of said clamp that presents a surface to the other feed point.

3. In a sewing machine for blind-stitching, the combination with an apertured 120

wall of the presser foot, extends forward beyond the left portion of the foot and upward about concentrically with the needle-path.

In the specific construction shown the work is fed wholly by an overhead feed mechanism comprising a yoke-shaped feed dog 80, the two arms 81, 82 of which depend on opposite sides of the presser foot opening 66 to straddle the paths of needle-reciprocation and work through the slots 76 in cooperation with the work-holding clamp 83. The feed dog is given a four-way movement from the head-shaft through the feed stem 85 which is slidable through pivot stud 86, and at its upper end is connected to crank pin 87 of a gear 88 that is coupled with the larger gear of gear couple 60. The pivot stud 86, (see Figs. 2 and 15) has a stem pivoted in a slide block 89 that is vertically slidable in slot 90 of an arm 91 that is normally stationary in the stitching frame, and the block may be clamped in any position of vertical adjustment by a nut 92 engaging the threaded stud 93 and block 89 so that the vertical position of the stud may be varied with consequent adjustment of the feed length. The arm 91 is pivoted as at 93 to the head frame, normally held against displacement by a spring latch 94 engaging an opening in the arm to fix it rigidly. By disengaging the latch the arm may be swung upwardly and toward the operator, to give access to parts below and rear of the feed mechanism, especially the hook, which is directly in rear thereof, for convenience for changing bobbins and the like. The cyclic operation of the feed dog is shown in Figs. 10 to 13.

The work holding clamp 83 is carried by a post 100 that extends into the lower arm 26 which is mounted on a slide block 101 (Fig. 1) vertically movable in guides in said frame arm, and normally held in elevated position by a strong leaf spring 102 which bears on the frame projection 103 and is adjustable as to tension by an adjusting screw 104 taking through a frame projection 105 and engaging a nut 106 mounted on the base of the spring 102. A depressing lever 107 pivoted in the frame at 108 serves, when lifted by a knee-lift, (not shown) to depress the clamp plate to facilitate insertion of the work.

The clamp member 83 is preferably mounted in a yoke plate 110 which has lateral, rearwardly-extending ears 111 in which is pivoted the clamp block proper which is thereby so sustained that it has a considerable capacity for tilting either its forward or rearward edge downward to yield for the passage of uneven thicknesses of material under the presser foot. The block is provided with an aperture 112 to accommodate the plunger 68, and at that side of said

aperture (the rightward side of the specific construction shown) along which the greatest thickness of goods is intended to pass in the usual working of the machine, the clamp block is provided with a supplemental clamp bar 114. This bar is located in a recess 115 in the block and is mounted on a stop screw that takes loosely through a hole in the bottom of the recess and engages the bar to define, adjustably, its maximum elevation above the block 83. In front and rear of the screw are springs 117 that hold the bar normally level and protruded somewhat above the block, but that give the bar the capacity to be depressed bodily and tilted on its post or screw 116.

Normally the clamp member 83 holds the fabric layers firmly against the underside of the presser foot, yielding bodily somewhat as need be to accommodate the pressure of the feed dog, tilting fore and aft under unbalanced pressures such as these caused by the passage of cross seams or other inequalities of the work through the machine, this tilting of the entire clamp block being supplemented by a yielding and tilting of the supplemental bar 114 in the clamp block under the influences of cross seams or other inequalities that are local to the thicker, or multiple layer zone of the work that passes over the righthand side only of the clamp plate.

The plunger, 68, for the class of work particularly intended to be handled, may be a flat, narrow vertical strip extending across the direction of feed and located across the leftward path of reciprocation, only, of the needle. This plunger may be an upstanding finger integral with a plunger lever 120 that is pivoted on a transverse shaft 121 within the frame. The plunger is caused to rise on every alternate reciprocation of the needle—i. e., its strokes in the leftward course—by means actuated from the main shaft. Thus a bell-crank lever 123, pivoted on or concentrically with shaft 121 has its forwardly-projecting arm arranged to overlie the plunger lever and connected by retractile spring 124 with the plunger-lever so that the plunger is positively depressed and yieldingly elevated. The pendant arm 125 of such lever 123 is connected by link 127 with a lever 128 (Fig. 16), the remote end of which is pivoted at 129 to the frame and the movable extremity of which bears a roller 130 that runs in the track of a face-cam 131 mounted on a vertical shaft 132 driven from the main shaft by a suitable one-to-two gear-couple 133.

It is important for many sewing operations, including the class of work hereinbefore suggested, that the plunger elevation shall depend somewhat upon the thickness of the goods and shall never rise above a level adjustable and predetermined, and in

- presser-foot, stitch-forming means working above said presser-foot, work-bending means for presenting work through said presser-foot-opening, work-feeding means, and 5 clamping means below said presser-foot comprising a yieldingly supported clamp-plate and a supplemental clamp-bar yieldingly supported by said clamp-plate.
4. In a sewing machine for blind-stitching, the combination with an apertured presser-foot, stitch-forming means working above said presser-foot, work-bending means for presenting work through said presser-foot opening, work-feeding means, and 10 clamping means below said presser-foot comprising a clamp-plate yieldingly and tiltably supported and a supplemental clamp-bar yieldingly and tiltably mounted in said clamp-plate.
- 20 5. In a sewing-machine for blind-stitching, the combination with a presser-foot, stitch-forming mechanism above said presser-foot including a needle arranged to vibrate between two paths of reciprocation 25 and a loop-taker cooperating therewith, feeding means arranged above and working through said presser-foot and having feed points on opposite sides of the two paths of reciprocation of the needle, and a work- 30 holding clamp below the presser-foot cooperating with the under side thereof and having surfaces presented to both feed points, the portion of said clamp presenting a surface to one feed point being yieldable 35 with reference to the portion of said clamp that presents material to the other feed point.
6. In a sewing machine for blind stitching, the combination with a presser-foot, 40 stitch-forming mechanism above said presser-foot including a needle arranged to vibrate between two paths of reciprocation and a loop-taker cooperating therewith, feeding means arranged above and working 45 through said presser-foot and having feed points on opposite sides of the two-paths of reciprocation of the needle, and a work-holding clamp below the presser-foot cooperating 50 with the underside thereof and having surfaces presented to both feed points, the portion of said clamp presenting a surface to one feed point being tiltable with reference to the portion of said clamp that presents material to the other feed point.
- 55 7. In a sewing-machine for blind-stitching, the combination with a presser-foot, stitch-forming mechanism above said presser-foot including a needle arranged to vibrate between two paths of reciprocation 60 and a loop-taker cooperating therewith, feeding-means arranged above and working through said presser-foot and having feed points on opposite sides of the two paths of reciprocation of the needle, and a work- 65 holding clamp below the presser-foot coop-
- erating with the under side thereof and having surfaces presented to both feed points, the portion of said clamp presenting a surface to one feed-point being bodily depressible and tilttable fore-and-aft with reference 70 to the portion of said clamp that presents material to the other feed point.
8. A blind-stitch sewing-machine comprising in combination a presser-foot having a plunger opening, free at one side thereof for the passage of multiple layers of material past said opening, some layers below said presser-foot and others over the front portion of the presser foot, and having feed point apertures, feeding means above the 75 presser-foot having points working through the presser-foot apertures, a clamp plate below the presser-foot having two surfaces opposed to said feed points, one of such surfaces being yieldable with respect to the other surface, a plunger arranged for co-operation with said presser-foot opening to present through it for cooperation with the material only that layer or layers of fabric which passes below the presser foot; stitch-forming mechanism comprising a needle and 80 loop-taking means working above the presser-foot and means to vibrate and reciprocate said needle; and means to actuate said plunger during alternate reciprocation of said 85 means.
9. Work clamping means for cooperation with the presser-foot of a blind stitch sewing machine comprising a yieldingly supported yoke, a clamp plate pivoted to tilt fore-and-aft in said yoke, and a supplemental bar mounted on said clamp plate and arranged to yield for bodily depression and for fore-and-aft tilting with respect to said 90 clamp plate.
10. In a blind stitch sewing machine, a stitching head having forwardly extending sides, a presser foot at the bottom of said stitching head, stitch-forming means above said presser-foot including a bobbin carrying hook near the rear of said head, a feed member supported above and working through said presser foot and having a bar extending in front of said hook and past the end of said needle arm bearing, said arm being shiftable forwardly away from the hook to free the bobbin for ready removal, and latch means normally maintaining said feed arm in the first stated position.
11. In a blind stitch sewing machine, a 100 frame comprising an upper arm carrying stitch-forming mechanism, such stitch-forming mechanism including a rotary hook mounted near the rear of said frame and a curved reciprocating needle cooperating 110 therewith, a presser foot carried by said arm below the stitch-forming mechanism, work holding means below said presser foot cooperating therewith, and feed mechanism comprising an overhead feed bar normally dis- 115
- 120
- 125
- 130

- posed in front of said hook, means for imparting feeding movements to said bar, and means permitting bodily displacement of said feed bar to give access to said hook.
- 5 12. In a blind stitch sewing machine, a frame comprising an upper arm carrying stitch-forming mechanism such stitch-forming mechanism including a rotary hook mounted near the rear of said frame and a curved reciprocating needle cooperating therewith, a presser foot carried by said arm below the stitch-forming mechanism, work holding means below said presser foot cooperating therewith, and feed mechanism comprising a vertical feed bar, means swiveling said feed bar between its ends, means for imparting four-way motion to the upper end of said feed bar, a pivoted supporting arm for said feed bar swivel, and latch means normally positioning said pivoted arm and operable to free said arm for pivotal displacement of the feed bar swivel to move the feed bar away from the hook.
- 10 13. In a blind stitch sewing machine, a frame comprising an upper arm carrying stitch-forming mechanism, such stitch-forming mechanism including a rotary hook mounted near the rear of said frame and a curved reciprocating needle cooperating therewith, a presser foot carried by said arm below the stitch-forming mechanism, work holding means below said presser foot cooperating therewith, and feed mechanism comprising an arm pivoted to the frame and slotted, a latch for normally holding said arm against pivotal displacement, a swivel vertically adjustable in said slot, a feed bar 85 slidable through said swivel, feed points on the lower end of said bar, and means pivotally connected with said bar for imparting four-way movement to its upper end.
- 15 14. In a blind-stitch sewing machine, the combination of a presser-foot having a work opening; stitch-forming means on one side of said presser-foot; a work-clamping member on the other side of said presser-foot, and having an opening; plunger means, working through said presser-foot and clamp-member openings; stop means for positively limiting the movement of the plunger toward the work, said stop means coacting with the clamp member for determination of its stopping position therefrom; means for vibrating the plunger to elevate it yieldably and depress it positively, a main shaft for supplying power to the moving parts, and positive connections between said shaft and the plunger-vibrating means.
- 20 15. In a blind-stitch sewing machine, the combination of a presser-foot having a work-opening, stitch-forming means on one side of said presser-foot, plunger means on the other side of said presser-foot, and ad-

justable stop means carried by the plunger 65 for cooperating with said presser-foot to limit the throw of the plunger, and means for actuating said plunger.

16. In a blind-stitch sewing machine, the combination of a presser-foot, stitch forming mechanism on one side of said presser-foot, plunger means working through said presser-foot, comprising a pivoted plunging lever, a stop movable with said plunger lever arranged to cooperate with the presser-foot and adjustable to vary its position with respect to the end of the plunger, means for actuating said plunger lever, and means extending to the exterior of the machine for adjusting said stop means with respect to 80 the plunger.

17. In a blind-stitch sewing machine, the combination of a presser-foot, stitch-forming mechanism on one side of said presser foot, plunger means working through said presser foot, comprising a pivoted plunger lever, a stop movable with said plunger lever arranged to cooperate with the presser-foot and adjustable to vary its position with respect to the end of the plunger, yielding 85 means for lifting said plunger and stop means, and means for adjusting said stop means with respect to the plunger.

18. In a blind-stitch sewing machine, the combination of a presser-foot, stitch-forming mechanism above said presser-foot, work-clamping means below said presser-foot, plunger means working through said presser-foot, comprising a pivoted plunger-lever, a stop-lever pivoted to the plunger-lever having one end arranged to cooperate with the presser-foot and adjustable with respect to the end of the plunger, and means for adjusting said stop lever upon said plunger.

19. In a blind-stitch sewing machine, the combination of a presser-foot, stitch-forming mechanism above said presser foot, a plunger-lever having an end arranged to work through said presser-foot, a stop-lever pivoted to the plunger-lever, and having an end arranged to coact with the presser-foot, and means accessible from the exterior of the machine for adjusting said stop-lever with respect to said plunger-lever, and means for adjusting said plunger-lever.

20. In a blind-stitch sewing machine, the combination of a presser-foot, stitch-forming mechanism above said presser foot, a plunger-lever having an end arranged to work through said presser-foot, a stop-lever pivoted to the plunger-lever, and having an end arranged to coact with the presser-foot, and means accessible from the exterior of the machine for adjusting said stop-lever with respect to said plunger-lever, and means for yieldably elevating and positively depressing said plunger-lever.

21. In a blind-stitch sewing machine, the

combination of a presser-foot having a work-opening, stitch-forming mechanism on one side of said presser-foot, a plunger cooperating with said presser-foot opening, a 5 stop for cooperation with the presser-foot adjacent said plunger-opening, adjustable with respect to said plunger and movable therewith, means for actuating said plunger, and means accessible from the exterior of the 10 machine for adjusting said stop with respect to said plunger.

22. In a blind-stitch-sewing machine, the combination of a presser-foot, stitch-forming mechanism above said presser-foot, a 15 plunger-lever working through said presser-foot, a shaft wherein said plunger-lever is pivoted having an eccentric portion, means accessible from the exterior of the machine for rotarilly adjusting said eccentric portion, a stop-lever pivoted to said plunger-lever and having a portion engaging said shaft eccentric whereby rotation of said eccentric adjusts the stop with respect to the plunger, and means for raising and lowering 20 said plunger.

23. In a blind-stitch sewing machine, the combination of a presser-foot, stitch-forming means above said presser-foot including a needle, vibratable for reciprocation in two 30 paths, and work-presenting means below said presser-foot comprising a plunger working through the presser-foot and arranged to cooperate with the needle at one path only of reciprocation of the latter, means for 35 raising said plunger on appropriate excursions of the needle, and adjustable means carried by said plunger cooperating with the under side of the presser-foot to limit the throw of the plunger.

40 24. In a blind-stitch sewing machine, the combination of a presser-foot, stitch forming mechanism on one side of said presser-foot, plunger means on the other side of said presser-foot having a portion to work 45 through the presser foot and a portion to coat with a portion of said presser-foot to limit the throw of the plunger, one of said coating portions being adjustable, and means for actuating said plunger.

50 25. In a blind-stitch sewing machine, the combination of a presser-foot having a work opening, stitch forming means on one side of said presser-foot, plunger means on the other side of said presser-foot having a portion 55 to present the work through said presser-foot opening and a portion to coat with a portion of said presser-foot to limit the work-bending throw of said plunger, and means for actuating said plunger yieldably to effect its said throw.

26. In a blind-stitch sewing machine, the combination of a presser-foot having a work-opening, stitch forming means on one side of said presser-foot, plunger means on the

other side of said presser-foot having a portion to present the work through said presser-foot opening and a portion to coat with a portion of said presser-foot to limit the work bending throw of said plunger, and means for actuating said plunger yieldably to effect its said throw and positively to effect its depression.

27. In a blind-stitch sewing machine, the combination of a presser-foot having a work opening, stitch forming means on one side of said presser-foot, plunger means on the other side of said presser-foot having a portion to work through said presser-foot opening and a portion to coat with a portion of said presser-foot to limit the work-bending throw of said plunger, one of said coating portions being adjustable to vary the limit of said throw, and means for vibrating said plunger arranged yieldably to effect its said throw.

28. In a blind-stitch sewing machine, the combination of a presser-foot having a work opening, stitch forming means on one side of said presser-foot including a needle vibratable for reciprocation in two paths, and work presenting means on the other side of said presser-foot comprising a plunger working through the presser-foot and arranged to cooperate with the needle at one path only of reciprocation of the latter, means for raising said plunger on appropriate excursions of the needle, said presser-foot and plunger having coating portions to limit the work-bending throw of the plunger, and means for adjusting one of said portions to vary the limit of said throw.

29. In a blind-stitch sewing machine, the combination of a presser-foot, stitch-forming mechanism on one side of the presser-foot, yieldingly mounted work-clamping means on the other side of said presser-foot; plunger means on the last said side arranged to work through the clamping means and presser-foot and having a portion to coat with a portion of said work-clamping means to limit the work-bending throw of the plunger, one of said portions being adjustable; and means for actuating the plunger.

30. In a blind-stitch sewing machine, the combination of a presser-foot having a work opening; stitch forming means on one side of said presser-foot; and work presenting means on the other side of said presser-foot comprising an apertured clamp member and a plunger vibratable through the clamp member and presser-foot; a stop member adjustably carried by the plunger arranged to coat with said clamp-member to limit the projection of the plunger through the latter; means for actuating the plunger and means for adjusting said stop-member.

31. In a blind-stitch sewing machine, the combination of a presser-foot having a work

opening; stitch forming means on one side of said presser-foot; work presenting means on the other side of said presser-foot comprising an apertured clamp-member and a plunger vibratable through the clamp-member and presser-foot; a stop member adjustably carried by the plunger arranged

to coact with said clamp-member to limit the projection of the plunger through the latter; means for actuating the plunger; and means accessible and operable while the machine is in operation, for adjusting said stop member.

CHARLES W. MUELLER.
